(57) **CLAIM**

The ornamental design for a straightening iron, as shown and described.

DESCRIPTION

FIG. 1 is a perspective view of a straightening iron showing a new design;

FIG. 2 is a top view thereof;

FIG. 3 is a bottom view thereof;

FIG. 4 is a side view thereof;

FIG. 5 is a front view thereof;

FIG. 6 is a top view of the lower half thereof; and,

FIG. 7 is a bottom view of the upper half thereof.

The broken lines are for illustrative purposes only and form no part of the claimed design.

The two portions of the straightening iron are shown separately for convenience of illustration.
